UNITED STATES PATENT OFFICE.

EDWARD EARLE, OF PHILADELPHIA, PENNSYLVANIA, ASSIGNOR OF ONE-FOURTH TO
JOHN D. LOCKE, OF PHILADELPHIA, PENNSYLVANIA.

DOWELING DEVICE.

1,153,841.

Specification of Letters Patent.

Patented Sept. 14, 1915.

Application filed July 2, 1912. Serial No. 707,313.

To all whom it may concern:

Be it known that I, EDWARD EARLE, of Philadelphia, in the State of Pennsylvania, have invented a certain new and useful Improvement in Doweling Devices, whereof the following is a specification, reference being had to the accompanying drawing.

My invention relates to devices for guiding drills to form sockets for dowel pins in wood joinery and is particularly adapted for embodiment in a portable device.

As hereinafter described my invention includes a block having a straight edge and a plane face at right angles thereto, a series of drill sockets of different diameters extending parallel with said face and at respectively different distances therefrom, and, a plate having its ends parallel with said straight edge and connected with said block by adjustable clamping means so that said plate serves to guide the work in proper relation with said drill sockets, and variably limit the depth to which drills may extend through said sockets into the work, by contact of the end of said plate with the drill stock.

My invention includes the various novel features of construction and arrangement hereinafter more definitely specified.

In the drawings; Figure I is an end view of a device conveniently embodying my invention and showing its relation to the work. Fig. II is a front elevation of the device shown in Fig. I. Fig. III is an end view of a modified form of my invention. Fig. IV is a front elevation of the device shown in Fig. III. Fig. V is an edge view of a piece of work showing dowel sockets made therein by the use of my device.

Referring to Figs. I and II:—The block 1 has the straight edge 2 and the plane face 3 at right angles thereto, and, the series of drill sockets 5, 6, 7, 8 and 9, of different diameters, extend through said block at right angles to said edge 2 and parallel with said plane face 3 at respectively different distances from the latter. The opposite face of said block 1 is arranged in steps respectively local to said sockets and at different distances from said plane face, and, the lines 11 are scored or otherwise marked on said stepped surface respectively parallel with the axes of said sockets in a plane at right angles with said plane surface

and intersecting the respective axis; so that 55 said lines 11 indicate the location of the axes of said sockets in planes normal to said plane surface and facilitate the location of said sockets with reference to marks scribed on the work as hereinafter described. Said 60 stepped construction of the block 1 permits the latter to be conveniently employed as a gage of thickness of the material in which the holes are to be drilled. The chip outlet channels 13 extend in said block transversely 65 to the axes of said sockets and open into the latter to permit the escape of chips therefrom during the drilling operation. The plane guide plate 15 is in contact with said plane face 3 of the block and projects 70 beyond said straight edge 2 to variably limit the depth to which drills may extend through said sockets, by contact of the end of said plate with the drill stock. In order to conveniently effect the longitudinal ad- 75 justment of said plate with respect to said block; said plate is provided with graduations representing units of length, in the direction of the length of said sockets, and has the two slots 16 engaging the ribs 17 80 on said block, and, said plate has the slot 18 for the clamp screw 19 which extends through the spring washer 20 in engagement with said block.

In the form of my invention shown in 85 Figs. III and IV the block 21 has the opposite end flanges 22 respectively engaging the edges of the plate 23 in lieu of the ribs and slots above described. Said plates not only serve to limit the extent to which the drills 90 may extend through the sockets in the blocks but also serve as guides for the work whereby the latter may be held parallel with the straight edges of the block and at right angles to the axes of the drill sockets. For 95 instance, as shown in Fig. I the work 25 is placed against the straight edge 2 of the block and extends parallel with its plane face 3, in contact with said plate, and, during the drilling operation the work is held 100 rigidly in such position in a vise or with any other suitable clamping means.

The location of the holes in the work may be predetermined by scribing the work as indicated at 28; each mark on the work be- 105 ing successively brought into registry with the proper line 11, on the block, indicating the location of the axis of the socket in the

block through which the drill 30 is extended to bore the desired hole or dowel socket in the work.

It may be observed that the respective 5 sockets 5 to 9 inclusive are located in the block at different distances from the plane surface 3 thereof so as to come centrally with respect to different standard thicknesses of material to be bored; the thickness 10 of the block at each socket therein being slightly less than the standard thickness of the material to be bored so that the mark scribed on the work may be seen to register with the selected line on the block.

15 Although the devices above described are thus conveniently constructed and arranged to facilitate the drilling of holes centrally with respect to standard thicknesses of material such as architectural trimmings, 20 moldings, picture frames, etc.; said devices may, of course, be employed in drilling holes at the predetermined distance of said sockets in the block from the plane face thereof, regardless of the thickness of the material 25 drilled. For instance, in Fig. V the material 30 is provided with two series of holes 31 which are successively located therein by shifting said material with respect to the smallest socket in the block.

30 It may be observed that the method of locating the dowel sockets indicated in Fig. V, to wit, in two series in staggered relation, is advantageous not only in that such staggered relation affords the maximum 35 thickness of material surrounding the dowels, but that the dowels thus located oppose their longitudinal strength to strains tending to break them transversely, whereas 40 dowels arranged in a single series only oppose their transverse strength to strains tending to break them transversely.

Although for ordinary joinery I prefer to provide blocks with drill sockets extending at right angles to the straight edge 45 thereof; it is to be understood that such blocks may be provided with drill sockets extending therethrough at different angles, in accordance with my invention. Moreover, although I find it convenient to employ plates such as I have described, in combination with the blocks containing the 50 drill sockets, in order to guide and hold the work with respect to said blocks, it is to be understood that such blocks may be employed with other means for holding them in connection with the work, and therefore I do not desire to limit myself to the 55 precise details of construction and arrangement herein set forth as it is obvious that various 60 modifications may be made therein without departing from the essential features of my invention as defined in the appended claims.

I claim:—

65 1. In a doweling device, the combination

with a block having a straight edge, a plane face at right angles thereto, and a series of drill sockets of different diameters parallel with said face and at respectively different distances therefrom, the opposite face of 70 said block being arranged in steps respectively local to said sockets, at different distances from said plane face, said stepped face having lines respectively parallel with the axes of said sockets in a plane at right angles with said plane face, and, chip outlet channels extending in said block transversely to the axes of said sockets and opening into the latter; of a plane guide plate 75 in contact with said plane face and projecting beyond said straight edge of said block at the ends of said sockets; said plate having three slots parallel with said sockets; said plate having graduations representing units 80 of length in the direction of the length of said sockets; two ribs on said block fitted to slide in two of said slots; a clamp screw on said block fitted through the other of said slots; and, a spring washer between said plate and the head of said screw; whereby 85 said plate may be adjusted longitudinally on said block at right angles with respect to the straight edge thereof to limit the depth to which drills may extend through said 90 sockets, by contact of the end of said plate 95 with the drill stock.

2. In a doweling device, the combination with a block having a straight edge, a plane face at right angles thereto, and a series of 100 drill sockets of different diameters parallel with said face and at respectively different distances therefrom, the opposite face of said block being arranged in steps respectively local to said sockets, at different distances from said plane face, and lines on 105 said stepped face respectively parallel with the axes of said sockets in a plane at right angles with said plane face; of a plane guide plate in contact with said plane face and projecting beyond said straight edge of said block at the ends of said sockets; said plate having three slots parallel with said sockets; 110 graduations representing units of length on said plate in the direction of the length of said sockets; two ribs on said block fitted to slide in two of said slots; a clamp screw on said block fitted through the other of said slots; and, a washer between said plate and the head of said screw; whereby 115 said plate may be adjusted longitudinally on said block at right angles with respect to the straight edge thereof to limit the depth to which drills may extend through said 120 sockets, by contact of the end of said plate with the drill stock.

3. In a doweling device, the combination with a block having a straight edge and a plane face at right angles thereto, a series of 125 drill sockets of different diameters parallel with said face and at respectively different

distances therefrom, and, the opposite face of said block having lines respectively parallel with the axes of said sockets in a plane at right angles with said plane face; of a 5 plane guide plate in contact with said plane face and projecting beyond said straight edge of said block; said plate having graduations representing units of length in the direction of the length of said sockets; 10 means slidably connecting said block and plate; and, clamping means; whereby said plate may be adjusted longitudinally on said block at right angles with respect to the straight edge thereof to limit the depth to 15 which drills may extend through said sockets.

4. In a doweling device, the combination with a block having a straight edge, a plane face at right angles thereto, and a series of 20 drill sockets of different diameters parallel with said face, and, the opposite face of said block having lines respectively parallel with the axes of said sockets in a plane at right angles with said plane face; of a 25 plane guide plate in contact with said plane face and projecting beyond said straight edge of said block; said plate having graduations representing units of length in the direction of the length of said sockets; 30 means slidably connecting said block and plate; and, clamping means; whereby said plate may be adjusted longitudinally on said block at right angles with respect to the straight edge thereof to limit the depth 35 to which drills may extend through said sockets.

5. In a doweling device, the combination with a block having a straight edge, a plane face at right angles thereto, and a series of 40 drill sockets of different diameters parallel with said face, and, the opposite face of said block having lines respectively parallel with the axes of said sockets in a plane at right angles with said plane face; of a plane guide 45 plate in contact with said plane face and projecting beyond said straight edge of said block; means slidably connecting said block and plate; and, clamping means; whereby said plate may be adjusted longitudinally on 50 said block at right angles with respect to

the straight edge thereof to limit the depth to which drills may extend through said sockets.

6. In a doweling device, the combination with a block having a straight edge, a plane 55 face at right angles thereto, and a drill socket parallel with said face, and the opposite face having a line parallel with the axis of said socket in a plane at right angles with said plane face; of a plane guide plate in 60 contact with said plane face and projecting beyond said straight edge of said block; and, clamping means; whereby said plate may be adjusted longitudinally on said block at right angles with respect to the straight edge 65 thereof to gage the depth to which drills may extend through said socket.

7. In a doweling device, the combination with a block having a straight edge, a plane face at right angles thereto, and a drill 70 socket parallel with said face; of a plane guide plate in contact with said plane face and projecting beyond said straight edge of said block; and, clamping means; whereby said plate may be adjusted longitudinally on 75 said block at right angles with respect to the straight edge thereof to gage the depth to which drills may extend through said socket.

8. In a doweling device, a block having a 80 straight edge, a plane face at right angles thereto, and a series of drill sockets of different diameters parallel with said face and at respectively different distances therefrom; the opposite face of said block being arranged in steps respectively local to said sockets, at different distances from said plane face, said stepped surface having lines respectively parallel with the axes of said sockets in a plane at right angles with said 85 plane face, and, chip outlet channels extending in said block transversely to the axes of said sockets and opening into the latter.

In testimony whereof, I have hereunto signed my name at Philadelphia, Pennsylvania, this first day of July, 1912.

EDWARD EARLE.
